UNITED STATES PATENT OFFICE.

ARTHUR E. SILCOX, OF LOWELL, MASSACHUSETTS, ASSIGNOR TO SACO-Lowell SHOPS,
OF BOSTON, MASSACHUSETTS, A CORPORATION OF MASSACHUSETTS.

BEAM-WARPER.

1,182,590.

Specification of Letters Patent.

Patented May 9, 1916.

Application filed January 2, 1914. Serial No. 809,866.

To all whom it may concern:

Be it known that I, ARTHUR E. SILCOX, of Lowell, in the county of Middlesex and State of Massachusetts, a citizen of the United States, have invented a new and useful Improvement in Beam-Warpers, of which the following is a full, clear, and exact description, reference being had to the accompanying drawings, forming a part 10 of this specification, in explaining its nature.

The present invention relates to a beam attachment or device for steadyng the beam of the warper while filling.

As is well known to those skilled in the art, a warper beam is supported to have not only a rotary movement from a driving drum but also movement relatively to the drum by reason of the accumulation 20 and increase of yarn upon the beam which tends to move the beam away from the drum. At the beginning of the wind when the beam has little yarn upon it, it has little weight and accordingly cannot bear against 25 the cylinder with sufficient pressure to run steadily. As the beam fills with yarn its weight increases which assists in maintaining it in proper contact with the driving cylinder, but until the beam becomes substantially filled with yarn it does not have sufficient weight to bear properly against the driving cylinder unless the beam is subjected to some steadyng influence.

It is accordingly the object of my invention to provide the beam with an attachment or device which will exert such steadyng influence and one, moreover, gradually diminishing in its intensity as the beam increases in weight by the increase of yarn 40 upon it.

My invention can best be seen and understood by reference to the drawings in which I have shown an embodiment thereof applied to one side of a warper, such portion 45 thereof only being shown as is necessary to illustrate my invention, in which connection it will be understood that the same devices for supporting and controlling the beam are employed at both ends thereof on either 50 side of the machine.

Figure 1 is a side elevation. Fig. 2 is also a side elevation showing a changed disposition and adaptability of the device forming the subject-matter of my invention. Fig. 3 is a front elevation of a detail

of construction to which special reference will hereinafter be made.

Referring to the drawings:—1 represents a portion of the frame at one side of the warping machine. 60 2 is the beam; 3 the flange-forming ends of the beam; 4 the beam shaft; 5 the driving cylinder or drum which is shown in dotted lines in Figs. 1 and 2, that the position of the beam and its support with relation thereto may be determined. 65

The beam is shown having a new and improved type of support which I have adopted for purposes of illustration inasmuch as my present device or attachment 70 efficiently cooperates therewith in the control of the beam. In this connection 6 is a supporting arm which is pivoted to the interior side or face of the frame 1 by means of an inwardly-projecting stud 7 on which 75 the arm turns. The arm 6 has secured to it a quadrant 8 which forms preferably integral connection with the arm and turns with it upon the stud 7. The outer edge of this quadrant is toothed and engaging 80 it is a pinion 9 operated by any suitable mechanism (not shown) and by which the quadrant may be turned and the arm with it, or be maintained in any adjusted position. When the machine is in operation 85 the arm is maintained in an upwardly-inclined engaging position substantially as shown in Fig. 1, and turned therefrom, after the filling of the beam, by the turning of the quadrant to a disengaging or 90 downwardly-inclined position where the beam may be removed in the usual manner. By reversing the process the arm carrying an empty beam may be returned to its original position. 95

Mounted upon the arm 6 is a sliding block 10 having a bearing 11 for the projecting end of the beam shaft and in which this shaft turns. The block is secured to the arm to slide longitudinally over the top surface 100 thereof as the beam is moved away from the driving cylinder by the accumulation and increase of yarn upon it. Secured to the outer end of the arm is a stop 13 which prevents the block sliding off the end of 105 the arm.

Secured to the frame adjacent the outer side thereof is an arm 15. This arm is pivotally secured to the frame by a stud 16 which lies below and just back of the beam 110

shaft when the beam is occupying its initial position with relation to the driving drum. The arm extends from the point of its pivotal retention upwardly, thence is curved 5 to extend forward over the projecting end of the beam shaft to rest thereon, and thence extends some distance beyond the same. Arranged upon the arm at the outer end thereof is an adjustable weight 17.

10 Secured to the inner end of the arm 15 to project forward therefrom is a finger 19. This finger is adapted to coöperate with a latch 20 by which the arm 15 may be held in a raised or disengaging position with relation to the beam shaft, substantially as shown in Fig. 2, or be released to a position of engagement with said shaft, as above described.

The latch 20 consists simply of a lever 20 pivoted by a pin 21 to the bifurcated end 22 of the stud 7 supporting the arm 6 and which projects beyond the outer face of the frame. The structural arrangement of the latch or lever 20 is such that it may be 25 turned to assume an engaging or disengaging position with relation to the finger. The engaging position is secured by turning down the latch when the finger will engage and rest upon the outer end thereof and in 30 which position the latch is maintained by the bearing of the end 23 of the latch against the outer end of the stud (see Fig. 3). From this engaging position the latch may be turned to a disengaging position 35 with relation to the finger simply by raising the arm 15 after which this arm may be lowered to engage the beam shaft as aforesaid.

The operation is as follows: When the 40 beam is empty or substantially empty at the beginning of the wind the weighted arm 15 resting upon the beam shaft will operate to exert considerable pressure for holding down the shaft upon its supporting bearing and insuring coöperation between the drum and the driving cylinder. As the beam 45 fills it moves outward longitudinally of its support and the weighted arm will accordingly bear against the beam shaft with a 50 gradually decreasing degree of pressure, the pressure of the arm, in other words, decreasing as the weight of the beam increases. In practice the disposition and arrangement

of the weighted arm 15 is such that it will exert a leverage of about 7:1 upon the shaft 55 of an empty beam, while upon the completion of the filling of the beam, the leverage will have decreased to about 1:1. After the beam has become filled and it is desired to dislodge the same from the machine by the 60 turning down of the arm 6 through the operation of the quadrant as aforesaid, or when the weight of the yarn becomes sufficiently great to eliminate the need of additional pressure, the arm 15 is raised into a 65 position of disengagement, as shown in Fig. 2, and held in this position by the latch. After a fresh beam has been placed in the machine the latch is released and the arm lowered into engagement with the beam 70 shaft, and the operation proceeds as before.

Having thus fully described my invention, I claim and desire to secure by Letters Patent of the United States:—

1. In a warper, the combination with a 75 beam, the beam shaft and a support for said shaft with relation to which support said shaft may have combined movements of rotation and inward or outward translation, of a lever fulcrumed to extend over 80 and rest upon said shaft and thence extend outwardly therefrom, whereby said lever may exert downward pressure upon said shaft gradually diminishing in intensity as said shaft moves translatable outward in 85 the operation of the machine, and means for pivotally supporting said lever.

2. In a warper, the combination with a beam, the beam shaft and a support for said shaft with relation to which support said 90 shaft may have combined movements of rotation and inward or outward translation, of a set of bent levers fulcrumed below said shaft and extending upwardly to extend over and rest upon the ends of said shaft 95 and thence extend outwardly therefrom, whereby said levers may exert downward pressure upon said shaft gradually diminishing in intensity as said shaft moves translatable outward in the operation of the machine, and means for pivotally supporting 100 said levers.

ARTHUR E. SILCOX.
